UNITED STATES PATENT OFFICE.

ALDEN M. DRAKE, OF WORCESTER, MASSACHUSETTS, ASSIGNOR TO THE HEALD MACHINE COMPANY, OF WORCESTER, MASSACHUSETTS, A CORPORATION OF MASSACHUSETTS.

GRINDING-WHEEL DRESSER.

Application filed July 31, 1922. Serial No. 578,664.

To all whom it may concern:

Be it known that I, ALDEN M. DRAKE, a citizen of the United States, residing at Worcester, in the county of Worcester and 5 Commonwealth of Massachusetts, have invented a new and useful Improvement in a Grinding-Wheel Dresser, of which the following, together with the accompanying drawings, is a specification.

10 The present invention relates to grinding machines, and in particular to means employed for dressing and truing the wheels of such machines.

The invention resides in the provision of 15 a wheel dressing and truing device which is readily shiftable into and out of operative relation to the grinding wheel,—the arrangement being such as to preserve and insure a rigid and firm mounting for the 20 dresser in its operative position, and, at the same time, permit of free access to the work when the dresser is not in use. Other and further objects and advantages of the 25 invention will appear in the following detailed description, reference being had to the accompanying drawings, wherein—

Fig. 1 is a view, in side elevation, showing a grinding machine with the invention applied thereto.

Fig. 2 is a detached view, on a larger scale, showing the construction of the dresser and its holder.

Fig. 3 is a plan view of the invention.

Like reference characters refer to like 35 parts in the different figures.

For purposes of illustration, the dresser is here shown as applied to an internal grinder, having at one end the usual spindle 1 for supporting and rotating the piece of 40 work 2, the spindle 1 being driven at moderate speed by a belt 3. At the other end of the machine, journaled in suitable bearings 4 of a slideable head 5, is the grinding wheel spindle 6, which is driven at high 45 speed by a belt 7. The movement of head 5 on suitable longitudinal ways provided by the machine frame, carries the rotating grinding wheel 8, on the end of spindle 6, into and out of contact with the work on spindle 1, in the manner well known in 50 machines of this class.

The wheel truing device, or diamond, is mounted on a suitable bridge 9, extending transversely of the machine and straddling 55 the ways in which the head 5 slides, said

bridge being secured to the fixed framework of the machine by means of suitable bolts 10, 10. Formed in the upper surface of the bridge 9 is a T-slot 11, for the reception of bolts 12, 12 which, when tightened by their nuts 13, 13, serve to retain in place, in any desired position of adjustment on the bridge 9, a mounting or holder 14 for the diamond.

This mounting or holder 14 presents an extended base portion in contact with the bridge 9, and integral with said base portion a cylindrical enlargement 15, which is laterally offset in the direction of wheel head 5, i. e., away from the work on spindle 1. The cylindrical enlargement 15 provides a bore 16 for the passage of a bolt or shaft 17, the latter carrying on its inner end, adjacent to its head 18, a substantially cylindrical member 19, having lugs 20, 20 for engaging the head 18, to constrain rotation 70 of member 19 with said bolt 17. The outwardly projecting end of bolt 17 is encircled by a washer 21, the latter being constrained against rotation relative to the bolt by a pin 22 which enters an elongated keyway 23. 80 Beyond the washer 21, the bolt 17 is reduced in diameter, and is threaded to receive a threaded split collar 24, adapted to be fixed in any desired position by a tightening bolt 25.

The member 19 presents an extended surface in contact with the inner face of enlargement 15, and provides an arm 26 extending laterally in the direction of the work spindle 1. At its free end the arm 26 is enlarged at 27, to provide a threaded opening for the retention and adjustment of a diamond dresser 28, the latter projecting inwardly toward the path of wheel 8. Interposed between the washer 21 and the collar 24 is a compressible annular member 29, here shown in the form of a spring washer, bearing resiliently at opposite sides against the collar 24 and the washer 21. At its outer end the bolt 17 provides a handle 30, by which it may be turned in the bore 16 of cylindrical enlargement 15.

In the normal operation of the grinding machine, the wheel dressing and truing mechanism occupies the inoperative position shown in full lines in Fig. 1, the handle 30 having been turned or twisted in a counterclockwise direction to carry the diamond 105 28 out of the path of the wheel, and out of the path of the head 5 which carries the 110

spindle 6. In this position, there is no obstruction to the travel of the grinding head toward the work, and furthermore, there is no interference by the diamond with the hand or arm of the operator, in the act of gauging or testing the work. When it is desired to dress or true the wheel, the latter is withdrawn from the work by movement of the head 5, and then the handle 30 is turned in a clockwise direction, until a lip 31 on member 19 engages a stop 32 on the base mounting 14. This disposes the dresser 28 into the dotted line position shown in Fig. 1, substantially in the plane of the axis of wheel spindle 6, and enables the wheel surface to be dressed by reciprocating the wheel back and forth in contact with the diamond.

The bore 16 provides a snug bearing for the bolt 17, and the extended contact between the opposing surfaces of member 19 and enlargement 15 effectually prevents any undue vibration or chattering of the diamond when in operative relation to the rotating wheel. The compressible member 29 serves to hold these opposing surfaces in close contact, while at the same time allowing the bolt 17 to be turned, by handle 30, to carry the diamond into and out of operative position. The tension of member 29 is adjustable to vary the tightness with which the diamond is held, by changing the longitudinal position of the collar 24 on the threaded portion of the bolt 17.

My improved mounting for the wheel dressing member is particularly advantageous because of the fact that the wheel dressing member is adapted to be moved into and out of its operative position with respect to the grinding wheel without changing the distance between the dressing member and the vertical plane of the grinding wheel axis. Therefore, with a given set-

ting of the wheel dressing member, the diamond dresser will always be returned to the same operative position with respect to the grinding wheel, regardless of the number of times that the wheel dressing member may be swung downwardly into its inoperative position. In other words, the dressing point is constrained to move in a substantially vertical plane which is parallel to the vertical plane of the grinding wheel axis.

55

I claim,—

1. In a grinding machine, a rotating grinding wheel, a bridge and a wheel dressing member adapted to be rendered inoperative by movement about a fixed axis provided by said bridge and extending substantially at right angles to the axis of rotation of said wheel.

60

2. In a grinding machine, a rotating grinding wheel, a wheel dressing member, and a support therefor providing a pivotal axis extending substantially at right angles to the wheel axis for the movement of said member into and out of operative position, said support providing also an extended surface in opposition to any other movement of said member, and means for exerting pressure to hold said member against said surface.

65

3. In a grinding machine, a rotating grinding wheel, a wheel dressing member, and a support therefor providing a pivotal axis extending substantially at right angles to the wheel axis for the movement of said member into and out of operative position, said support providing also an extended surface in opposition to any other movement of said member, means for exerting pressure to hold said member against said surface, and means for varying said pressure.
